HENRY ROSWELL SWAN, SR., OF HUNTINGTON, WEST VIRGINIA.

CAR-COUPING.

1,120,562.

Specification of Letters Patent.

Patented Dec. 8, 1914.

Application filed November 14, 1913. Serial No. 800,979.

To all whom it may concern:

Be it known that I, HENRY ROSWELL SWAN, Sr., a citizen of the United States, and resident of Huntington, in the county 5 of Cabell and State of West Virginia, have invented an Improvement in Car-Couplers, of which the following is a specification.

My present invention relates to car couplers, my object being to provide an arrangement including certain novel details of construction whereby a gravity latch member 10 may be utilized upon the tail of the knuckle and the parts moved to and from closed position without the destructive friction and 15 danger of breakage existing in couplers at the present time, and a further object of my invention is to provide certain connections by means of which the latch member when raised will be automatically held in 20 such position.

In the accompanying drawings, forming a part of the specification, Figure 1 is a plan view of a draw head, partly broken away and in section to illustrate the knuckle and 25 its latch member. Fig. 2 is a vertical longitudinal section through the parts shown in Fig. 1 and taken substantially on line 2—2 of said figure. Fig. 3 is a partial transverse vertical section through the parts shown in 30 Fig. 1, taken substantially on line 3—3 of said figure, and Fig. 4 is a detail perspective view of the knuckle removed.

Referring now to these figures, the draw-head A is substantially hollow in order to 35 provide for the movement therein of the inner portion of the knuckle B, the latter being of solid structure and connected to the draw-head by the usual knuckle pin C. The upper and lower walls of the draw-head 40 A are provided with the usual central openings a and a' respectively, the functions of which are well-known, and in accordance with my invention the lower wall of the draw-head is also provided with a substantially 45 rectangular opening a² adjacent its side wall a³ toward which the inner tapering tail portion b of the knuckle B projects, it being noted that this tail portion b is substantially elongated so that its inner end 50 bears against an inwardly projecting portion a⁴ of the side wall a³ when the end hook d of the latch member D is in engagement with the lower wall opening a² and the coupler parts are in locked position. The wall 55 a³ also has the usual inwardly projecting portion a⁵ with which the body b' of the

knuckle engages in closed position and the additional bearing or engagement between the tail b and the wall projection a⁴ distributes the strain throughout the length of 60 the knuckle and eliminates the danger of breakage of the knuckle in a considerable degree.

The inner portion of latch member D is journaled on the tail b and confined against 65 the shouldered end of the knuckle body b' by means of a cotter-pin b² or other equivalent fastening member and is thus free to rock on the tail b to an extent sufficient to permit its hook d to descend into and ascend 70 out of, the lower wall opening a² as will be seen by a comparison of the full and dotted lines in Fig. 3, the hook end of this latch member having a slot to receive the end link of a pull chain or lever E and having a 75 transverse pin d' whereby the pull chain or lever may be engaged and held, it being noted particularly from Figs. 2 and 3 that this pull chain or lever extends outwardly through the upper wall opening and is provided with a ball E' of considerable weight 80 whereby when the latch member is raised and the weight E falls to one side of the opening a upon the curved upper wall of the draw-head, the latch member will be 85 held in raised position. It is to be understood, however, that the weight of ball E' is only sufficient for the purpose stated, and is not such as to prevent it from being jarred into the upper wall opening when 90 two couplers come together, and which it is intended it should do in order to allow the latch member to drop and latch the parts.

As will be noted particularly from Figs. 1 95 and 3 the hook end of the latch member D is laterally extended in a direction toward the outer end of the knuckle in order to form a shoulder d² adapted to engage the inner side face of the body b' of the knuckle 100 B, when the latch member is raised to the position shown by the dotted lines in Fig. 3 and thus limit such upward movement of the latch member and prevent its hook end from engagement with the upper wall of 105 the draw-head during the swinging movement of the knuckle. Thus it will be apparent that the coupler is opened from a closed position, as shown by the heavy lines in Fig. 1, side view of same being shown 110 in Fig. 3, to an open position, as shown by dotted lines in Fig. 1, by the one operation

of pulling the chain or lever, which extends outwardly through the opening *a* in the draw-head *A*.

Thus it will be seen that the construction 5 presented by my invention affords strength and will be effective and durable in use for the purposes before stated.

I claim:

10 The combination of a draw-head having an opening through its lower wall at one side of its center, a knuckle pivoted in the draw-head and having a reduced tail extension and a shoulder at the inner end of said

extension, a latch member mounted on said tail extension adjacent the said shoulder 15 and having a shoulder extending laterally from its side adjacent the knuckle shoulder and adapted to engage the face of the knuckle body when the latch member is raised, and means for raising the latch member and swinging the knuckle. 20

HENRY ROSWELL SWAN, SR.
